UNITED STATES PATENT OFFICE.

HARRY ALLEN WEBSTER, OF LANCASTER, PENNSYLVANIA.

DRAFTING INSTRUMENT.

1,072,539.

Specification of Letters Patent.

Patented Sept. 9, 1913.

Application filed February 27, 1913. Serial No. 751,180.

To all whom it may concern:

Be it known that I, HARRY ALLEN WEBSTER, a citizen of the United States, residing at Lancaster, in the county of Lancaster 5 and State of Pennsylvania, have invented a new and useful Drafting Instrument, of which the following is a specification.

The present invention relates to improvements in drafting instruments, the primary 10 object of the invention being the provision of a means whereby the pencil or crayon point carried by one member of a bow compass or a jointed compass, may be properly adjusted relatively to the centering pin or 15 needle of the compass, there being provided a spring clamp for retaining the pencil or crayon against the normal tendency to slip upwardly during the manipulation of the instrument, and there further being provided 20 an adjustable stop for coaction with the upper end of the pencil or crayon to project the same when necessary and also to assist in limiting the upward movement thereof during the manipulation of the instrument. 25

With the foregoing and other objects in view which will appear as the description proceeds, the invention resides in the combination and arrangement of parts and in the 30 details of construction hereinafter described and claimed; it being understood that changes in the precise embodiment of the invention herein disclosed can be made within the scope of what is claimed without departing from the spirit of the invention. 35

In the drawings—Figure 1 is a side elevation of a spring bow compass with the present invention applied thereto. Fig. 2 is a side elevation of a jointed connection of a 40 jointed compass with the present invention applied thereto. Fig. 3 is a side elevation of the crayon holding clip and adjusting device on an enlarged scale. Fig. 4 is a bottom plan view thereof. Figs. 5, 6 and 7 are 45 views of a modified form of pencil or crayon adjusting mechanism.

Referring to the drawings, and more particularly to Figs. 1, 2, 3 and 4, the numeral 1 designates the center carrying member of the instrument, and 2 the center needle, the same being of usual construction, while the member 3 thereof is provided with the elongated spring terminal 4 which coacts with the short spring terminal 5, both of said terminals being spaced apart as at 6, Fig. 4, to

provide the crayon receiving recesses 7 and 8, said terminals 4 and 5 having a normal tension toward each other so as to retain the crayon 9 in the desired clamped position. This clip or clamp holds the crayon 9 so 60 that the same is permitted the necessary movement when adjusting the same but under normal conditions is held against longitudinal movement.

In order to provide a means for adjusting the crayon 9 longitudinally within the clip, a supporting plate 10 is connected to the outer end of the long terminal 4 and carries the threaded shank or screw 11, which is disposed parallel to the crayon 9, 70 the same having mounted thereupon the milled adjusting disk or nut 12, which is disposed to have a portion thereof as at 13 abut the upper end of the crayon 9 and thus provide a means to limit the upward 75 movement of the crayon during the manipulation of the instrument and at the same time provide a means whereby when the disk is rotated to move downwardly upon the screw 11, to project the pointed end 80 of the crayon after the same is worn, thus providing a means to place the writing end of the crayon 9 in the desired relation to the centering needle 2, without the necessity of adjusting the needle 2 as is the usual 85 practice. Thus the needle 2 may be retained at the desired adjustment at all times, and the disk 12 may be manipulated to give the proper projection to the writing point of 90 the crayon 9.

In the form of instrument shown in Figs. 5, 6 and 7, the members 15 and 16 carrying the clamping members 17 and 18, are normally spaced but are moved to and from each other by means of the headed screw 19, 95 as clearly illustrated in Fig. 7. Thus the pencil or crayon 9' is properly positioned between the members 17 and 18 while the receiving screw 20 which corresponds to the screw 11 is attached to the member 18 100 through the medium of the threaded shank and nut 21. Upon the screw 20 is disposed a disk (not shown) similar to the disk 12 and the crayon 9' is held against outward movement in a similar manner to the structure heretofore described, and is projected by the manipulation of a similar disk. 105

The present invention contemplates the use of the screw 11 and disk 12 on any form of compass, thereby providing a means 110

whereby the lead or crayon 9 is adjusted as worn without the necessity of changing the centering point 2.

What is claimed is:

- 5 1. A drafting instrument, having a crayon holder and adjusting device, including a friction clip for the crayon, a screw carried by the clip and disposed parallel to the crayon when in the clip, and a disk threaded upon the screw and projecting to engage the upper end of the crayon in the clip to feed the crayon through the clip in one direction and to hold the crayon against retraction in the opposite direction.
- 10 2. A drafting instrument, having a crayon holder and adjusting device, includ-

ing a friction clip for normally retaining the crayon against longitudinal movement, a screw carried by the clip, and a disk threaded upon the screw and projecting to 20 engage the upper end of the crayon while in the clip to feed the crayon through the clip in one direction and to hold the crayon against retraction in the opposite direction.

In testimony that I claim the foregoing 25 as my own, I have hereto affixed my signature in the presence of two witnesses.

HARRY ALLEN WEBSTER.
